United States Patent Office.

HENRY C. SMITH, OF LAWRENCE, KANSAS, ASSIGNOR TO AMERICAN MORTISING-MACHINE COMPANY, OF BOSTON, MASSACHUSETTS.

Letters Patent No. 105,603, dated July 19, 1870.

IMPROVEMENT IN MORTISING-MACHINE.

The Schedule referred to in these Letters Patent and making part of the same.

Be it known that I, HENRY C. SMITH, of Lawrence, State of Kansas, have invented certain Improvements in Mortising-Machines, of which the following is a specification.

The invention relates to certain improvements to a mortising-machine patented by me the 4th day of September, A. D. 1860, said Letters Patent being numbered 29,920, and said improvements relate chiefly to the mode of operating the machine. It will be perceived, by examining the drawings of the original patent, that the machine is operated by a lever with two arms, and upon the end of the short arm is attached a pawl, with a claw meshing into a ratchet-wheel, said wheel being secured to a shaft bearing pinions which gear into a stationary rack, &c., and that these gearings are moved by the operating lever in working the machine.

These devices for operating the machine failed in practice on account of their complexity, also being unwieldy and liable to get out of order, and the improvements are to remedy these defects.

Description of the Drawing, &c.

The accompanying drawing shows all the parts sought to be patented as improvements in this device.

The letter A represents the block which bears the cutting and feeding devices, so arranged as to slide between two upright posts, b b, of the frame B.

K is the lever by which the machine is operated with the hand, and k is a short armed lever, attached to the end of the operating lever, and connected by link l to the ring-lever or pawl m.

n is the lug playing into the ratchet o, and o is a ratchet operating as a nut upon the upright screw P, which operates as a shaft, by which the block A, receiving the frame to which is attached the cutting apparatus, is raised or lowered at pleasure.

q is a crank attached to the upper end of the screw P, by which the block may be raised or lowered.

r is a shaft, the lower part of which is a screw, the end of which rests upon the solid part of the frame B, upon which screw is a hooked nut, s; and t t are gauges attached to the horizontal part of the frame, which rests upon the timber to be operated upon.

General Description.

I make use of the lever K in operating the ma-

chine. It is pivoted to the block A, as will be seen by the drawing, and also has a short-armed lever at its extremity, which arm is slotted, and near its upper end has a pin, and around this pin passes a part of the link l, making its connection to it, which link is hooked into the pawl or ring-lever m, which ring-lever fits loosely upon the upright screw P. This ring-lever has also a mortise, through which is a lug, n, meshing into the horizontal ratchet-wheel. By raising the lever K, the short-armed lever k and link l carry forward the ring-lever m, the lug n playing into the ratchet-wheel o and depressing the lever K. The pawl n is pushed back for another turn, and at each depression of the lever K the cutting apparatus performs its work.

Upon the shaft and screw r, I have placed a hooked nut, s. The use of this hooked nut is to fasten a chain upon one horn of the nut, passing the chain under the timber, and hooking it upon the other horn.

By turning the crank in one direction the machine will be made fast to the timber, and it is loosened again by turning the crank in another direction.

I have also placed gauges t t upon the horizontal part of the frame, by turning which downward over the edge of the timber the mortises will be cut in a true line, without measuring, &c.

In thus arranging the feeding apparatus of the cutting-machine, I have made the machine more effective, taking up less room, and rendered it less likely to get out of order, and less complex in its movements.

I claim—

The combination and arrangement of the operating lever K, the short-armed lever k, the link l, the pawl or ring-lever m, the lug n, operating the ratchet o, the ratchet o, the same being arranged and operating the screw P, and the screw P, the whole being arranged and operating the block A, bearing the cutting device, substantially in the manner and for the purpose described.

Also, the arrangement of the gauge t upon the frame B, substantially for the purpose described.

HENRY C. SMITH.
